INCANDESCENT LAMP STEM

Alfred Hofmann, Palisade, and Victor Anderson,
North Bergen, N. J., assignors to Alfred Hof-
mann & Company, West New York, N. J., a
corporation of New Jersey

Application December 3, 1931, Serial No. 578,700

5 Claims. (CL. 176—35)

This invention relates to incandescent lamp stems and the manufacture thereof, referring particularly to electric lamps in the nature of bulbs or tubes containing electrodes or filaments and either exhausted of air or filled with a particular gas, and whether for illumination, radio or other purposes. The invention is shown illustratively applied to the stem part of the modern types of incandescent filamentary lamp, the bulb or tube of the completed lamp being tipless, and the air exhausting (and sometimes gas filling) of which is effected through a small air pipe entering the lamp chamber through the stem. The general objects of the present invention are to afford an improved lamp stem and resulting lamp, and improved method and means of manufacture thereof. Particular objects are to improve the lamp stem in regard to structure, form and strength; to improve the exhausting or filling steps by the use of a larger size air pipe, and by entering such pipe into a lower point in the lamp chamber; to afford an improved sealing of the leading-in wires; and to dispense with the preformed or tubular "flare" which is usually an element of the completed stem part.

A further object is to simplify and improve the manufacture of lamp stems by dispensing with the customary steps of preforming the flare, from glass tubing, and separately preforming the filament anchor or post when used, from a glass rod, and subsequently combining these and the air pipe and leading-in wires into a unitary stem, and blowing a perforation for communication of the air pipe with the interior; this improvement permitting the manufacture of the complete stem part, containing the essential components, by a single operation of molding the same from molten glass, thereby to produce the complete stem, shaping it with body, with skirt or flared flange and with anchor post, combining with it the preformed air pipe, and sealing in the lead wires and pipe, all in one operation and apparatus; resulting in cheapened production and improved structure of lamp stem and lamp.

Other and further advantages of the invention will be explained in the hereinafter following description of one or more illustrative embodiments thereof or will be understood to those conversant with the subject. To the attainment of such objects and advantages the present invention includes the novel incandescent lamp stem, and the novel method and means of manufacture thereof, and the novel features of procedure,

structure and detail herein illustrated or described.

In the accompanying drawings Figure 1 is a side elevation of an incandescent lamp stem embodying the present invention, the position of the subsequently applied bulb or tube being indicated enclosing the lamp chamber in which are contained the stem and connected parts.

Fig. 2 is an edge elevation of the lamp stem of Fig. 1.

Fig. 3 is a top plan view partly in horizontal section on the line 3—3 of Fig. 1.

Fig. 4 is a side elevation of a common form of incandescent lamp embodying the features shown in Figs. 1 to 3 and completed to the extent of 15 the attachment of the filament and the insertion and fusion of the stem with the bulb and the exhaustion and sealing of the lamp.

Fig. 5 is a side elevation of a modified lamp stem; and Fig. 6 in transverse section shows a 20 further modification.

Fig. 7 shows in elevation another modified form. Fig. 8 in elevation shows still another form, and Fig. 9 a top view thereof.

Figs. 10, 11 and 12, in transverse section, show 25 various illustrative modifications in the form of the stem body, for example to embody four, five or other plural number of lead wires.

Fig. 13 in top view, and Fig. 14 in elevation, show a modified form of the upper end of the 30 molded anchor post of Figs. 1-3; and Fig. 15 is a perspective, with variations.

Fig. 16 is a top view, and Fig. 17 is an elevation of a modified form of lamp stem embodying this invention, with the preferred character of mold- 35 ing means therefor indicated in dotted lines.

In respect to structure the present product differs radically and essentially from the usual lamp stem part, which is built up from a preformed upright tubular glass "flare", so called, 40 having its bottom end open and having its top end fused, flattened and closed to embed and seal a short length of the lead wires, and to receive and seal the small air pipe extended upwardly through the length of the tubular flare, 45 and to receive the preformed filament anchoring post. The present invention as distinguished therefrom may be described as consisting of an upright body which preferably is not tubular but which on the other hand is formed with a closed 50 bottom, and such closed bottom having an integral outstanding skirt for subsequent connection with the lamp bulb, and a preformed air pipe extended through and embedded and sealed in such closed bottom and open thereabove for 55

the subsequent exhaustion of air from the lamp chamber, and one or two or a greater number of lead wires extended through and embedded and sealed in the closed bottom of the body and preferably also in the upper portion of the body thereabove, the wires having therefore an extended length of sealing, and issuing from the body for subsequent attachment thereto of the lamp filament or electrode; and the structure 10 is believed to be broadly new in the aspect of the stem with lead wires sealed therein, or the stem with air pipe sealed therein, or both. The terms "upright" and the like are used in a relative sense assuming the longitudinal length of 15 the lamp is held vertical with its base downward.

Referring in detail to the drawings, the particular embodiment shown in Figs. 1 to 4 comprises a lamp stem of glass or the like, the body 20 or main portion 20 of which may be described as upright, as it has substantial longitudinal extent or height in the direction of the length of the lamp. The body comprises mainly an upper portion 21 and a bottom or section 22, merging 25 together, the bottom being disklike or otherwise transversely closed, and the upper portion comprising the glass material above the bottom, being preferably of reduced cross section as compared with the bottom and preferably formed 30 of substantial height and with a laterally opening air recess as will be described. The closed section or bottom is shown as formed with an integral outstanding skirt 23 adapted subsequently to be fused and united with the bulb 35 or container of the lamp chamber, such skirt being preferably flared downwardly. In a sense the closed lower end or bottom section 22 of the stem body is a sort of nucleus or center from which extend integrally the upper portion 40 21, the skirt 23, and the air pipe to be described; any of which extensions may be varied in shape or extent to suit any particular requirements.

In Fig. 1 the upper portion of the body is shown as constituted of a plurality of separate 45 or spaced apart sides or columns, and when so formed the upper ends thereof are preferably connected by an integral top 24. Enclosed by the columns, or formed otherwise, is shown an air recess or laterally opening aperture 25 located 50 in the body above the bottom, and the bottom is formed with an air perforation 26 shown as opening into the recess 25, thus giving communication to the air pipe for exhausting purposes. Below the bottom, when the skirt 23 is flared, 55 it is formed a concavity or underneath recess 27.

An air pipe 30 containing a through passage 31 is shown extended through the body bottom 22 and sealed therein, its passage 31 opening out 60 through the perforation 26 into the lateral recess 25 and thus affording subsequent communication between the inside of the lamp and the atmosphere for exhausting and filling purposes. While the air pipe might be formed in the molding process, it is preferably a preformed pipe of correct 65 length, inserted in the mold.

One or more lead wires 35 in this case two, are shown, extended through the bottom 22 and sealed therein, and preferably the lead wires are carried interiorly through the upper portion 21 of the body, thus giving an extensive sealing length, which may be substantially the full height of the body of the lamp stem. Exterior wire portions 36 constitute free ends for subsequent connection to terminal contacts, while interior free

ends 37 issue from the upper part of the body to be subsequently shortened and disposed suitably for connection of any form of filament or electrodes.

The description of the illustrated lamp stem is substantially completed by reference to the supporting extension or post 40, which is an optional feature but usually preferable to give support to the middle or other part of the filament of an illuminating lamp, or for supporting any other 10 electrode. The post 40 is shown as extended upwardly from the upper portion 21 of the body or preferably directly from the center of the top 24.

All of the portions thus far described are preferably 15 constituted of a unitary integral piece of glass or similar vitreous matter, with the exception of the lead wires which may be composed of dumet metal or other suitable conducting material; and the post 40 may be wholly or partly an 20 attached component. The lamp bulb, tube or enclosing wall 45 is indicated in Fig. 1, its lower portion 46 being shaped in by fusion and united to the outer edge of the skirt 23, after the completion of the stem and attachments. The lamp at 25 this stage is shown in Fig. 4, enclosing the evacuated or gas filled chamber 41, and the air pipe 30 being sealed off and closed at 32, while the wires carry the filament 49, steadied by attachment to the anchor button 41 at the top of the post 40, 30 which may have embedded anchor wires 42 for the purpose.

The described lamp stem is not merely of high strength and practical efficiency, but is of such form as to lend itself to effective and large scale 35 manufacture by a molding process, molten or viscous glass being forced under pressure into a properly constructed mold as will be described. The advantages heretofore enumerated are attained. The lead wires 35 are sealed within the 40 bottom 22 of the stem and upwardly through the body clear to the point where they issue for attachment of filament.

While each lead wire might be composed of special or dumet wire having a coefficient of ex- 45 pansion about the same as that of glass, with this invention a lead wire may readily be employed built up of three lengthwise united sections, for example an outer length of copper, a middle length of special or dumet wire and an interior 50 length of nickel wire, the middle or special wire preferably being made longer than usual and long enough to extend the full length for which the lead wire is embedded in the stem body.

The air pipe 30 is readily fused and sealed in 55 the stem bottom during molding, and its interior passage maintained open at the perforation 26 for communication with the recess 25. The air pipe is thus substantially shortened as compared with that in a lamp stem built up upon a tubular 60 flare, since the air pipe does not extend to the top but may terminate directly at the upper side of the bottom 22 of the structure. Having a shorter projecting length the pipe is stronger, and it is readily sealed off and closed, as indicated in Fig. 65 4, a temporary flame shield being located between the closing point 32 and the stem body, for example shaped into the concavity 27 within the skirt 23, thus to protect the stem body and skirt 70 and connected parts from injury from the sealing heat. A cylindrical shield can be applied surrounding the pipe and lead wires when fusing the skirt to the bulb.

By the disclosed arrangement the air pipe 30 75

exhausts the lamp from a low or even the lowest point within the lamp chamber, instead of from a point at the top of the usual stem. This is found to be of advantage and assistance in reducing 5 moving vaporous and gaseous contents of the lamp. No difficulty is encountered in ensuring the opening of the pipe passage 31 into the lamp chamber or lateral recess 25, and the step is eliminated of supplementally fusing the stem at an 10 interior point while directing air pressure through the pipe to force a perforation. At the same time this invention permits an air pipe to be employed of substantially larger diameter than usual, in fact as large as desirable up to the point of conflict with the lead wires.

Before describing an illustrative method of production, the modified structures shown in Figs. 5 etc. will be referred to, understanding that the principles may be used in greatly varied forms 20 and that the illustrated forms are merely examples. One modification is the omission of the anchor or supporting post, as when a filament is employed that needs no intermediate support, and Fig. 5 shows such modification. This figure shows also that the lateral recess 25^a may be varied in size, it being shown much shortened. Otherwise the structure is like Figs. 1-3, and Fig. 3 represents a section taken on the line 3—3 of Fig. 5.

30 The lateral aperture 25^a, or the lower portion of it, represents a lug or abutment, or an opposed pair of them projecting in the mold; the top end of the air pipe 30 abutting against the same, thus insuring that the air pipe is kept open and communicates with the recess. Preferably the mold is fed with glass adjacent to this point and a portion of the recess 25 or 25^a may represent a plunger operable to move through the mold and cut off the supply; or such movable plunger may 40 at first constitute the abutment for the pipe 30 and subsequently move across the mold and cut off the flow. The form shown in Figs. 1-4 has been manufactured by the use of a movable plunger adjacent to a fixed abutment, or rather 45 opposed abutments or lugs, in the mold, thus giving the elongated recess 25^a, but these two mold parts, the plunger and lugs, might be non-adjacent, so as to form one recess for the abutment and air pipe and a second one for the plunger, the 50 form shown in Figs. 1-4 however giving minimum weight consistent with strength and other requirements.

Instead of employing opposed abutments to produce a through recess as in Figs. 1-5 a mold abutment at one side only might be employed, affording the result shown in Fig. 6, considered as a cross section at the line 3—3 of Fig. 5, the body 21^a being completely closed at the far side and the recess 25^a confined to the near side but having sufficient extent to give a clear air opening for the perforation 26.

In the form shown in Fig. 7 the cross piece or top 24 of the stem body is omitted, so that there remain two spaced apart columns 21^b constituting the upper portion of the body, with a recess 25^b between them into which the perforation 26 enters.

In Figs. 8 and 9 the stem body is reduced in height by the omission of much of the upper portion shown in the other figures, the short body however still comprising the closed bottom 22^c and the upright portion 21^c thereabove. No lateral recess is here necessary as the perforation 26^c opens upwardly directly into the lamp chamber. 75 The outlying flange or skirt 23^c is not belled or

flared downwardly as in Figs. 1-7, but is shown substantially flat or even shaped slightly upwardly at the rim.

Fig. 10 indicates a cross section view of a modified lamp stem, which may be considered as taken substantially at the section line 3—3 of Fig. 5. In this case four wires 35^d are shown and the stem body 21^d is shaped to enclose and embed these and to terminate with a closed bottom 22^d extended into the flange or skirt 23. The air perforation or exit 26^d of the air pipe is shown delivering into a lateral recess 25^d preferably taking out of one side only of the stem body. Fig. 11 shows a different form on the same principles, five wires 35^e being shown extending through the body 21^e, and the lateral recess 25^e providing communication for the perforation 26^e. Fig. 12 shows a case where eight lead wires 35^f may be embodied in the stem body 21^f, the body here as before being formed with a lateral communicating recess 25^f for the perforation 26^f.

The Fig. 11 form can be molded as described, while the Figs. 10 and 12 forms would require a special mold with side parts laterally retracting from the reentrant curves at the sides.

As a new article of manufacture the lamp stem hereof may be described as comprising a skirt or flare section 22, 23 for subsequent fusion to a lamp bulb, said section being relatively shallow or short in a longitudinal direction, combined with 30 an exhaust pipe 30 projecting integrally near the axis of the stem at the exterior side of said skirt section, said skirt section being transversely closed except as to the air passage 31 in said exhaust pipe, which passage extends through the skirt 35 section and is open near the axis at the interior thereof for subsequent exhaustion of air; also a body portion 20 projecting integrally at the interior side of said skirt section, said body portion being relatively deep or long in a longitudinal 40 direction, and having an open recess 25 with which the passage 31 connects near the axis, and leadwires 37 extended through said skirt section and longitudinally embedded and sealed in said body portion. Except for the preformed exhaust 45 pipe, the glass parts, namely the skirt section and body portion, preferably consist of a unitary piece of molded glass, with which the pipe is integrally fused, and in which the leadwires are sealed; and the manufacturing may be practically performed 50 by molding operations and apparatus such as originally fully described and illustrated in this application.

For convenience the molding shape of a molding plunger 69 and lugs 61 are indicated in dotted 55 lines on Fig. 1, these combining to form the central or lateral recess 25 of the lamp stem body. By dispensing with one of the lugs 61 and deepening the other the recess thereof will be unilateral as in Fig. 6, or in Figs. 10, 11 and 12.

Figs. 13 and 14 show a modification in the anchor post 40 as otherwise shown in Figs. 1-3, indicating that with this invention the post may be molded with the rounded button or top 41 as seen in Fig. 4, and the anchor supports or 65 supporting wires 42 embedded in the button during the molding process; this readily being accomplished by drilling the required number of small bores into which the wires 42 are inserted before the molding, leaving a small projecting end, but 70 arranged to avoid contact or approach of one to another. In the Fig. 15 form the anchor wires are in greater number than in Fig. 14, and are set longitudinally to the post, subject to being bent to any required angle in completing the lamp. 75

Figs. 16 and 17 show a lamp stem wherein the body 20^e has no lateral aperture, it being hollow, open at the top, and round or square or other hollow shape, with six or other number of lead wires 35^e carried vertically through it, and with the preformed air pipe 30 opening at 26^e into the lower end of the wall or interior space of the hollow body. The molding arrangements may be as indicated in dotted lines. The mold line or division between the upper and lower mold blocks may be somewhat above the center at one side and below at the other. This permits the hopper 52^e and gate 51^e to be placed laterally, and the plunger 53^e operated therein; which in turn allows the cut off plunger 69^e to be arranged for insertion between the gate and the mold cavity, thus not having to cross the mold space or interrupt the continuity of the wall of the stem body.

There have thus been described an incandescent lamp stem and a means and mode of manufacture thereof embodying the principles of the present invention; and since various matters of procedure, structure and detail may be modified without departing from the principles it is not intended to limit the invention to such features except to the extent set forth in the appended claims.

What is claimed is:

1. As an article of manufacture a lamp stem comprising: a skirt or flare section for subsequent fusion to a lamp bulb the same being relatively shallow or short in a longitudinal direction, an exhaust pipe projecting integrally near the axis of the stem at the exterior side of said skirt section, said skirt section being transversely closed except as to the air passage in said exhaust pipe which passage extends through the skirt section and is open near the axis at the interior thereof for subsequent exhaustion of air, a body portion projecting integrally at the interior side of said skirt section the same being relatively deep or long in a longitudinal direction, and having an open recess with which said passage connects near the axis of the stem and leadwires extended through said skirt section and longitudinally embedded and sealed in said body portion.

2. A lamp stem as in claim 1 and wherein the skirt section and body portion are constituted of a unitary piece of molded glass and the exhaust pipe being a preformed glass pipe fused integrally with said skirt section.

3. As an article of manufacture a lamp stem comprising: a skirt or flare section for subsequent fusion to a lamp bulb the same being relatively shallow or short in a longitudinal direction, an exhaust pipe projecting integrally at the exterior side of said skirt section, said skirt section being transversely closed except as to the air passage in said exhaust pipe which passage extends through the skirt section and is open at the interior thereof for subsequent exhaustion of air, a body portion projecting integrally at the interior side of said skirt section the same being relatively deep or long in a longitudinal direction, and formed with a laterally open recess within which opens such air passage, and leadwires extended through said skirt section and longitudinally embedded and sealed in said body portion.

4. A lamp stem as in claim 3 and wherein the body portion is formed with a recess opening laterally in a plurality of directions dividing the body portion into spaced columns within which the leadwires are embedded.

5. As an article of manufacture of lamp stem comprising: a shallow flare section for subsequent fusion to a lamp bulb, an exhaust pipe fused with and projecting at the exterior side of said flare section, said flare section being transversely closed except as to the air passage in said exhaust pipe which passage extends through the flare section and is open at the interior thereof for subsequent exhaustion of air, a body portion formed integrally with and projecting longitudinally at the interior side of said flare section, and leadwires extended through said flare section and longitudinally embedded and sealed in said body portion, and issuing therefrom at an interior point, said body portion provided with an interior extension beyond the point of issuance of the leadwires for the support of an electrode.
